PLANER GAUGE

Lester H. Dierking, Detroit, Mich., assignor to
Edward H. Kramer, Detroit, Mich.

Application July 27, 1942, Serial No. 452,466

5 Claims. (Cl. 33—162)

This invention relates to improvements in planer gauges. Such articles as now made include the provision of a body having an inclined upper face and a block movable therealong so that the respective heights of bearing faces upon the block may be set the desired height above the base upon which the body rests; means are also provided for then holding the block immovable relative to the body. However such setting is usually relatively rough and no provision is made for fine adjustment of the block along the inclined face.

It is an object of this invention to provide a planer gauge having means for finely and accurately adjusting the setting of the block so that the bearing faces thereon may be adjusted for height to a fraction of a thousandth of an inch.

Another object of the invention is to provide such a planer gauge including means for rapidly setting the block to approximately the required position prior to employment of the fine adjustment above referred to.

A further object of the invention is to provide a planer gauge having the advantages above stated which is relatively cheap and simple to manufacture, and which is simple and quick to adjust.

Having thus briefly stated some of the objects and advantages of the invention I will now proceed to describe it in detail with the aid of the accompanying drawing, wherein:

Figure 1 illustrates a side view of the invention, and

Figure 2 is a plan view thereof.

Figure 3 is a section on the line 3—3 of Figure 2.

Figures 4 and 5 are sections on the lines 4—4 and 5—5 respectively of Figure 3.

Referring to the drawing, 1 designates a body having a flat underside 2 to rest upon a bed of a machine (not shown), and an inclined upper side 3 which is longitudinally slotted at 4 intermediate of its length so that spaced longitudinal ways 5 are formed on opposite sides which are undercut at 6, and the depth of the slot 4 is such as to receive a longitudinal screw 7 the axis of which is parallel with the tops of the ways 5. One extremity of the screw 7 is supported in a bearing 8 formed in one extremity of the body 1, and the opposite extremity of the screw terminates in a portion 7a of reduced diameter which is supported for rotation in a bearing formed in a plug 9 mounted in an appropriate opening 10 formed in the body 1 from its op-

posite extremity. Fixedly secured to the screw 7 adjacent the plug 9 and upon its portion 7a of reduced diameter is a worm wheel 11 which meshes with a worm 12 upon a spindle 13 which is transversely mounted in the body 1. 14 denotes a knurled head upon the outer extremity of the spindle 13 and between the said head and the body 1 a calibrated dial 15 is secured around the former to register with a suitable index mark 16 upon the body 1. To further insure that no axial movement of the screw 7 occurs an annular groove 17 may be formed around the said screw adjacent one extremity to receive a pin 18 mounted in the body 1.

Mounted for longitudinal sliding movement along the ways 5 is a block 20 provided with stepped bearing faces 21 and 22 which are parallel with the underside 2 of the body. A bolt 23 extends through the block 20 and the sides of the head 24 thereof project beneath the undercut sides of the ways 5 so that the block may be held immovable upon the body by tightening a nut 25 upon the upper extremity of said bolt. Extending upwardly at right angles from the underside of the block 20 intermediately of its width is an aperture 26 having a screw engaging member 27 mounted for axial movement therein, and provided upon the underside of the said member are partial threads 28 which are normally retained in engagement with the screw 7 by a helical spring 29 extending between the closed upper end of the aperture 26 and the adjacent end of the member 27, and formed transversely through the latter is a slot 30 the upper side of which is inclined.

A transverse opening 31 is formed from one side of the block 20 and is counterbored at its outer extremity as shown at 32. Mounted for axial movement in the opening 31 is a release pin 33 having one side 34 tapered to coact with the tapered side of the slot 30 to raise the screw engaging member 27 and disengage its partial threads 28 from the screw 7 upon inward movement of the said pin. Housed in the counterbore 32 is a helical spring 35 which bears against a head 36 of increased diameter integral with the release pin 33 thereby tending to force the latter outward and permit the partial threads 28 of the member 27 to remain in their screw engaging position. Formed in the head 36 intermediately of its length is a peripheral slot 37 into which a stop 38 mounted upon the block 20 projects. This stop limits the axial movement of the release pin 33.

Suitable index marks 40 may be provided upon

the inclined upper face of the body to register with an index mark 41 upon the block to assist in the rough setting of the said block.

Adjustment of the height of the block 20 is obtained in the following manner. The head 36 of the release pin 33 is pressed inward thereby retracting the screw engaging member 27 so that its partial threads 28 become disengaged from the screw 7, and the spring 29 is compressed. Then the block 20 may be freely moved to its approximate setting. Upon release of the head 36 the spring 35 again moves the release pin 33 outward and the spring 29 causes re-engagement of the partial threads 28 with the screw 7. Then by rotation of the spindle 13 through its knurled head 14, and through the worm 12 and worm wheel 11, the screw 7 is rotated and by this rotation the block 20 is moved along the ways 5 by engagement of the partial threads 28 with the said screw.

While in the foregoing the preferred embodiment of the invention has been described and shown it is understood that the construction is susceptible to such alterations and modifications as fall within the scope of the appended claims.

What I claim is:

1. A planer gauge comprising a body having its upper side longitudinally inclined, a screw mounted for rotation upon said body having its axis parallel with said upper inclined side, means for rotating said screw, a block longitudinally slideable upon said inclined upper side having at least one bearing face thereon, a screw engaging member mounted for movement upon said block having partial threads thereon to engage said screw, means normally holding said partial threads in engagement with the screw whereby rotation of the latter moves the block along said upper side, said member being transversely slotted and one side of said slot being inclined to the member axis, and a release pin mounted for movement in said block and extending through said slot, said pin having an inclined face formed thereon to coat with the inclined face of the slot whereby upon movement of the pin in one direction the member is moved and its partial threads are disengaged from the screw.

2. A planer gauge comprising a body having its upper side longitudinally inclined, a screw mounted for rotation thereon and having its axis parallel with said inclined upper side, a worm wheel on said screw, a spindle mounted transversely in the body, a worm on said spindle in engagement with the worm wheel, a calibrated dial fixed on said spindle to register with an index mark on said body, a block longitudinally slideable upon the upper inclined face of the body, said block having at least one bearing face there-

on, a screw engaging member on said block, means normally holding said member in engagement with said screw whereby rotation of the spindle imparts movement to the block, and means for releasing the member from the screw to permit independent longitudinal movement of the block upon said body.

3. A planer gauge comprising a body having its upper side longitudinally inclined, a screw mounted for rotation thereon having its axis parallel with said inclined upper side, a spindle mounted for rotation transversely through the body, coating means on said screw and spindle for rotating the former by rotation of the latter, a block longitudinally slideable upon the upper inclined side of the body, said block having at least one horizontal bearing face thereon, a screw engaging member on said block, means normally holding said member in engagement with said screw whereby rotation of the latter moves said block, and means for releasing the member from the screw to permit independent movement of the block on the body.

4. A planer gauge comprising a body having its upper side longitudinally inclined, a screw mounted for rotation thereon having its axis parallel with said inclined upper side, a spindle mounted transversely through the body, coating means on said spindle and screw turning the latter by rotation of the former, a bearing block longitudinally slideable on the upper inclined side of the body, means on the block normally engaging the screw whereby rotation of the latter moves the block along the body, means for releasing said engaging means, and means carried by said block for locking the latter relative to said body.

5. A planer gauge comprising a body having its upper side longitudinally inclined, a screw mounted for rotation thereon having its axis parallel with said inclined upper side, a spindle mounted transversely through the body, coating means on said spindle and screw turning the latter by rotation of the former, a calibrated dial fixed on the spindle to register with an index mark on the body, a bearing block having at least one horizontal bearing surface thereon longitudinally slideable on the upper inclined side of the body, a member carried by the block having partial threads thereon, means normally holding said member so that the partial threads engage the screw whereby rotation of the latter moves the block, means extending into the block for moving the member whereby the partial threads are disengaged from the screw, and means carried by the block for locking the latter relative to said body.

LESTER H. DIERKING.
